United States Patent Office.

STEPHEN PERRY AND JOSEPH JOHN PERRY, OF LONDON, ENGLAND.

Letters Patent No. 70,893, dated November 12, 1867.

IMPROVEMENT IN INKSTANDS.

The Schedule referred to in these Letters Patent and making part of the same.

TO ALL WHOM IT MAY CONCERN:

Be it known that we, STEPHEN PERRY and JOSEPH JOHN PERRY, both of Red Lion Square, London, England, manufacturers, have invented certain new and useful "Improvements in Inkstands," and we do hereby declare that the following is a full and exact description thereof, reference being had to the accompanying sheet of drawings and to the letters of reference marked thereon.

The said improvements consist chiefly in the employment of a hollow stopper, of vulcanized India rubber, or other suitably elastic material, which is fitted in an aperture in the top of the inkstand, and which, when forced inward, compresses the air and causes the ink to rise in a tube, whose upper end terminates in a cup or mouth-piece, into which the pen is dipped. The said tube and cup may be made solid with the inkstand and may be arranged at the side of the stopper, or a separate tube of glass or other suitable material, may be inserted through the centre of the stopper. In either case the tube must extend nearly to the bottom of the inkstand, so that the compressed air cannot escape through the said tube without causing the ink to rise. The cup, stopper, and tube may also be formed in one piece, the two latter being of soft rubber, and the cup being hardened or strengthened by a ring of metal, wood, or other hard or inflexible substance.

Description of the Drawings.

Figure 1 is a plan of the top of an inkstand with the tube and dipping-cup formed solidly thereon.

Figure 2 is a section of the same on the line xx .

Figures 3 and 4 are a similar plan and section of an inkstand, with a separate tube fitted into the stopper.

Figures 5 and 6 are like views of an inkstand, with stopper and tube formed of one piece of rubber.

Figure 7 represents a modification of the same, and

Figure 8 represents a stopper provided with a flexible tube.

Like letters indicate the same parts in each of the figures.

The reservoir or body A of the inkstands may be made of earthenware, porcelain, glass, or other suitable material, and may be of any desired form and size. In the inkstand represented in figs. 1 and 2, the aperture B for the stopper C is, by preference, formed with the neck or collar a, to give sufficient bearing surface to insure a perfectly air-tight joint between the said aperture and stopper, at whatever position the latter may be adjusted. The parallel portion of the stopper which fits the said aperture is made hollow, the thickness of the material being just sufficient to give it the required stiffness, without impairing its elasticity or flexibility. The head C' of the stopper C is made solid, to render the same sufficiently rigid to be conveniently adjusted.

When the reservoir A is partially filled with ink, and the stopper C is introduced into the aperture B, air is enclosed in the space in the reservoir above the surface of the ink, and the slightest compression of this air will cause the ink to rise in the tube D. The stopper C can be adjusted to cause the ink to rise to any desired height in the cup D¹, and this will be the case however small the quantity of ink in the reservoir, provided it is sufficient to cover the lower end of the tube D. By raising or withdrawing the stopper C slightly in its aperture, the ink will descend in the tube D, and will remain in that position till the stopper C is again depressed. The ink is by this means saved from evaporation, and is kept in good condition till it is all used.

In the modified arrangement of parts represented in figs. 3 and 4, the tube D, which passes through the stopper C, is by preference made of glass. The said tube is formed with a protuberance or enlargement D², just below the cup D¹, which protuberance fits tightly in the aperture in the stopper C, and yet allows the said tube to be removed therefrom when desired. With the exception of the central perforation for the reception of the tube D, the said stopper is made the same as that shown in figs. 1 and 2, and is fitted to slide air-tight in the aperture B of the inkstand. When this stopper is depressed in the said aperture, the ink rises into the cup D¹, and can be maintained at any desired height therein, or allowed to sink back into the interior of the inkstand by adjusting the stopper C, as already described.

Figs. 5 and 6 represent the stopper C and cup D¹, formed in one piece, the stopper being of soft rubber and the cup of hardened rubber. The tube D is in this case dispensed with, the central portion of the stopper C, which is lengthened for the purpose, serving instead of the said tube. Fig. 8 represents a modification of this mode of construction. Instead of using the tube D, a tube, E, of India rubber, or other flexible material, may be attached to a short tube on the bottom of the cup D¹, as shown in fig. 8. The lower end of this flexible

tube rests on the bottom of the reservoir A, and allows the inkstand to be used with very little ink in the said reservoir.

What we claim as our invention, and desire to secure by Letters Patent, is—

1. The employment of a hollow stopper, formed of vulcanized India rubber, or other suitable elastic material, in combination with the reservoir A, tube D, and cup D¹, for the purpose and substantially in the manner set forth.

2. The tube D, formed with the protuberance D², and fitted into the stopper C, for the purpose and substantially in the manner set forth.

3. Forming a stopper, cup, and tube, in one piece, of hard and soft rubber combined, substantially as described.
